AUTOMATIC TALKING MACHINE

Samuel Kresberg, Brooklyn, and Victor Peter-fesa, Bronx, N. Y., assignors to The Capitol Automatic Music Co., Inc., New York, N. Y., a corporation of New York

Application August 7, 1934, Serial No. 738,794

14 Claims. (Cl. 274—10)

It is among the general objects of the present invention to provide an efficient, coin controlled, automatic magazine talking machine which will be wholly automatic in its operation and which will accommodate a large number of records in a single magazine from which they may be automatically selected for playing in a predetermined order or any one of which may be manually selected.

10 Another object of the present invention is to improve and simplify the construction of such a machine to reduce its size and to provide positive means whereby its operation is rendered more reliable in the face of inexpert operation.

15 Other objects of the present invention are the provision of improved selective record shifting means from the magazine to and from a turn-table, improved means for automatically controlling the movement of the sound box so that it will properly cooperate with the record disc, and an electrical timing device to stop the other mechanisms while a record is playing.

20 One form of the invention which has been selected for purposes of illustration is shown in the drawings, of which

25 Fig. 1 is a rear elevation of an improved machine;

Fig. 2 is a fragmentary rear elevation showing a record disc in playing position;

30 Fig. 3 is a front view showing the record magazine shifted to a receiving position;

Fig. 4 is a similar view showing the record magazine in locked position;

35 Fig. 5 is a plan view of the machine in receiving position;

Fig. 6 is a plan section taken on the line 6—6 of Fig. 3 showing the record shifted to playing position;

40 Fig. 7 is an end elevation looking in the general direction of the record magazine;

Fig. 8 is an end elevation looking in the direction of the turn-table;

45 Fig. 9 is a fragmentary view showing the method of seating the tone arm on the record;

Fig. 10 is a similar view showing the tone arm positioned in correct position on the record;

50 Fig. 11 is a sectional elevation taken on the line 11—11 of Fig. 1;

Fig. 12 is a plan section of the tone arm shifted to starting position;

Fig. 13 is a section taken on the line 13—13 of Fig. 12;

55 Fig. 14 is a section taken on the line 14—14 of Fig. 12;

Fig. 15 is a sectional elevation taken on the line 15—15 of Fig. 1;

Fig. 15A is a view taken in direction of 15A—15A of Fig. 15;

Fig. 16 is an electrical wiring diagram of the 5 machine;

Fig. 17 is a section on the line 17—17 of Fig. 15 showing the clutch shifting mechanism.

The general framework of the machine is enclosed in a suitable cabinet (not shown). The 10 framework comprises upper and lower substantially rectangular cast metal frames 20 and 21. Upon it are mounted or suspended the various mechanisms controlling the operation of the machine. The upper and lower frames are connected by the upright posts 22, 23, 24 and 25 and the intermediate straps 26 and 27. Across the front and rear of the machine a pair of horizontal guide rails 28 are provided, which are fastened as indicated in Figs. 1 and 3 and provide additional rigidity to the framework. The framework is mounted in the cabinet (not shown) preferably upon the lugs 29 secured to the side walls thereof.

A turn-table 30 is positioned on the right hand side (see Fig. 3) upon the upper end of a vertical shaft 31 driven by the usual phonograph motor 32 and having a governor 33 to regulate the speed. This may be of an approved type and is suitably geared with the vertical shaft 31. The 30 turn-table shaft and its mechanism is spring suspended from a cross-plate 34 which in turn is fastened to a supplemental frame 35 rigidly mounted on the upright posts 24 and 25, and the intermediate straps 26 and 27.

The disc records R are contained within a magazine M which can be automatically raised and lowered so as to bring each of the records in the magazine into line with the turn-table 30 in a definite sequence. Also it can be manually positioned so as to similarly position any one of the records in the magazine. The magazine consists of a rectangular framework 36 having a series of inwardly projecting arms 37 in spaced relation to one another. The projecting arms 37 are disposed on opposite sides and have the disc plate 38 fastened at the points 39 as shown at Fig. 6. This disc plate 38 aids in forming a solid support for the records, insures against displacement due to a sudden jolt, and because of the perforations 40 permits of the shifting of records R into playing position with little friction.

The magazine framework 36 is mounted to slide upon a pair of guide rods 41 fixed at their upper and lower ends to the metal frames 20 and 21 re-

35

40

45

50

55

spectively. A pair of anti-friction rollers 42 at the upper ends of framework 36 engage the outer side of the guide rods 41 and a pair of anti-friction rollers 43 on the lower ends of framework 36 engage the inner sides of such rods. Cord 44 attached to an inwardly extending lug 45 on the top of framework 36 is fastened to a grooved pulley 46 journaled in the uprights 47 on the top metal frame 20. A spiral cam 48 formed integral with the grooved pulley 46 and a retaining plate 49 fastened at its side has a cord 50 attached to it which extends downwardly to the upper end of a heavy spring 51. The lower end of the spring 51 is connected to the lower frame 21. The purpose of the spring 51 is to partially counter-balance the weight of the magazine with the records therein and because of the spiral cam 48 spring 51 exerts an almost uniform pull on the magazine in the different adjusted positions. To further aid in counter-balancing the magazine a weight 52 is suspended from the upper portion of the framework 36 so as to slide within guide tube 53 mounted on the frame 21.

Since all disc records are provided with the usual center openings a pair of fixed vertical rods 54 and 55 are used to prevent displacement of the records R from the magazine. The upper vertical rod 54 is detachably fixed to a cross-piece 56 on the frame 20 with the set-screw 57. A ring 58 attached to rod 54 is provided to remove this centering means so that the disc records can be changed as desired. The lowermost rod 55 is securely fixed to a bracket support 59 mounted on the lower metal frame 21. Referring to Figs. 2, 3 and 15 it will be noted that the adjacent ends of the rods 54 and 55 are tapered and spaced apart a definite distance at a point in line with the turn-table 30. This permits only the record directly in line with the turn-table 30 to be taken from the magazine M and placed in a playing position. The records are shifted from the magazine M onto the turn-table 30 and back again to position in the magazine by a horizontal shifting carriage C which consists of a pair of curved arms 60 and 61 partly encircling a standard size record R and connected at the turn-table end with the straight portion 62. The shifting carriage C reciprocates upon a pair of horizontal guide rails 28 fixed to the upright posts 22, 23, 24 and 25 and the intermediate straps 26 and 27. Lugs 63 on the curved arms 60 and 61 extend above and below the width of the guide rails 28 and with the studs 64 projecting to guide the shifting carriage C. The rear of the carriage C also has a depending lug 65 with similar studs 64 to insure against vertical shifting of the carriage C.

On the lower end of the depending lug 65 (see Figs. 1 and 2) a pivot pin 66 has a slot connection with the upper end of a shift lever 67, the lower end of which is pivotally mounted at 68 on the rear central portion of the lower frame 21. A link 69 pivotally connected at its end to the shift lever 67 is connected at its other end by a pivot pin 70 to a rocker arm 71. The rocker arm 71 is preferably formed of cast metal and is of considerable width (see Fig. 15) at the bottom to form a rigid bearing for the arm on pivot pin 72. The spring 73 allows for a slight longitudinal motion by arm 71 upon pin 72. A pivot pin 74 slightly below pin 70 on the rocker arm 71 engages a longitudinal slot 75 on the outer end of a link 76 and the inner end of the latter is connected to a crank arm 77 on the end of the shaft 78. Referring to Figs. 1 and 2 the rocker arm 71 has the cam way 79 cast integral with it. The latter serves the purpose of

engaging and disengaging the teeth 80 on the magazine M as the shifting carriage carries a record to and from the turn-table T.

A curved lever 81 pivoted on the top frame at 82 extends downwardly to a curved portion provided with the roller 83 in contact with the cam-way 79 as shown in Fig. 1. A detent plate 84 on the central portion of the curved lever 81 is directly in line with one of the teeth 80 on the movable magazine M. As the shifting carriage C takes a record from the magazine M the cam-way 79 on the rocker arm 71 is shifted to the left (see Fig. 2). The guide posts 85 serve the purpose of steadyng the curved lever 81. A spring 86 is attached to one of the guide posts 85 with its opposite end pinned to the curved lever 81. The purpose of the spring 86 is to urge lever 81 to the left so that it will follow cam-way where it is rocked to the left until detent plate 84 engages one of the teeth 80 on magazine M. This insures a perfect locking of the magazine in any position selected while a record is playing.

A pair of springs 87 extending from the top to bottom of the magazine framework 36 provide a resilient stop for the record R when the shifter carriage C returns same to its proper position in magazine M so that the holes in the record are directly in line with the vertical rods 54 and 55 (see Figs. 6 and 15). The magazine M is provided at its lower end with an inwardly extending foot 88 which has a steel insert 88' resting upon the outer ends of a lifting arm 89 (see Figs. 3, 4 and 15), and a pivot 90 on the rear of the worm gear bracket 91. A shaft 92 journaled in the bearings 93 on the lower frame 21 carries the spiral cam 94 so proportioned as to give a definite rise to the lifting arm 89 when turned in the direction indicated by the arrow. A roller 95 on the lifting arm 89 rests on the spiral cam 94 and gives the magazine M a definite amount of lift corresponding to the space between the records R which are shown as sixteen in number. A ratchet wheel 96 is fastened at the rear of the spiral cam 94 and a pawl 97 pivoted at 98 engages one of the teeth due to the action of the spring 99. The spiral cam 94 fastened to the ratchet wheel 96 rides free on the shaft 92 and the pawl 97 permits rotation in one direction only.

Fig. 4 shows the lowest position the magazine M assumes. It will be noted that the roller 95 on the lifting arm 89 has passed from the highest position of the cam 94 through the channel 100 to the position shown. A bridging member 101 integral with the cam 94 has attached to its outer end the guard rail 102 which forms the channel 100 for the roller 95 to pass through. Since the action of spring 51 and the weight of the records R tend to counter-balance one another, the whole magazine descends from the highest point to the lowest point at a moderate speed but to safeguard against a slight overthrow of the magazine M as the knob 100 is turned to this particular point the guard rail 102 is employed which extends to the point 103. The cam 94 with the channel 100 guides the roller 95 in perpendicular alignment with the magazine M so that the records R at that point are in positive register with the turn-table T. As an illustration, the cam 94 due to the weight of the magazine and records descending could shift the cam 94 slightly to the right which would mean that the uppermost record would not be in proper alignment with the turn-table T, and as the knob 100, that raises and lowers the magazine, can only be turned in one direc-

tion would mean that the whole procedure would have to be repeated. A curved guide rod 104 is fastened to the shoe portion of the lifting arm 89 which rides in the slot 105 in the lower frame 21. The front side of the spiral cam 94 has the two teeth 106 cast integral with it. The latter engage a clutch 107 on the same shaft. The clutch 107 is slidably mounted on the shaft 92 having a pin 108 on the shaft 92 engaging a slot 109. Referring to Figs. 15 and 17 a clutch lever 110 pivoted at 111 is provided with the shifter pin 112 which rides in the groove 113. A spring 114 tending to hold the clutch in engagement with the teeth 106 is fastened at one end to clutch lever 110 and the forward end to a lug on the lower frame 21. The free end of lever 110 is held against a flat ring 115 fastened to the face of a worm wheel 116 on the shaft 78. Flat ring 115 has a groove 117 which allows the clutch lever 110 to place clutch 107 in engagement with the cam 94.

Referring to Figs. 3, 15 and 15A a knob 190 on the outside of cabinet (not shown) has a toothed end which engages a clutch member on a sprocket only when the knob is depressed at the same time disconnecting a circuit switch. The sprocket connects with a chain 118 (see Fig. 15) to a sprocket 119 on the shaft 92. When the clutch 107 engages the teeth 106 on the cam 94 the whole can be turned as a unit in the direction indicated by the arrow. A bent strap 120 attached to the upper part of the magazine frame 36 terminates in a pointer 121 which is bent to appear before a program frame 122 which has the various selections 123 indicated in a manner corresponding with the arrangement of the records in the magazine. By depressing the knob 190 the operator can shift to any record desired, but when knob 190 is released the shaft 78 starts to rotate, throwing the clutch lever 110 out of the groove 117 on the flat ring 115. This action of the clutch lever 110 releases the clutch 107 from the teeth 106 on the cam 94 and as a result will not turn with the shaft 92. The cam 94 at this stage is disengaged from the shaft 92 to safeguard against any change of record while the machine is in operation. The shaft 78 is provided with a worm wheel 116 driven by a worm 124 on the cross shaft 125 journaled in the worm gear bracket 91 and at its outer end in the bearing lug 126. Shaft 125 is driven by a spring belt 128, passing on a pulley 127 on shaft 125, and the small pulley 129 on the shaft of a motor 130. The motor 130 is resiliently suspended from a lug 131 cast as part of the frame 21. Two leather strips 132 with a number of thin flexible straps of metal 133 are fastened to the lug 131 at the upper ends, the flexible straps 133 being bent to fit the diameter of the motor and being secured thereto. It has been found that in combination with a spring belt 128 this motor will operate successfully even though the pulleys 127 and 129 are slightly out of alignment.

Referring to Figs. 1 and 11 a cam 134 on the shaft 78 engages a roller 135 on the lower part of a raising lever 136 pivoted at 137 on an upright lug 138 on the lower frame 21. The raising lever 136 has an L-shaped projection 139 disposed above it, the opposite end of which is secured to the lower end of a long vertical shifting bar 140 extending and sliding between straps 141 secured to the frame. Near the center of bar 140 a spring 142 is secured, the lower end being fastened at 143. The tension of the spring 142 always tends to hold the shifting bar

140 downward and with the L-shaped projection 139 bearing down on the raising lever 136 with the roller 135 in contact with the cam 134. As shown in Fig. 1 a bracket 144 is fastened to the shifting bar 140. It extends to the right and has a V-shaped end 145 which bears in a groove 146 arranged on the lug 65 of the shifting carriage C. This secures the shifting carriage C in proper relation to the magazine M when the records R are selected. As a record R is taken from the magazine M the shifting bar 140 is raised by the cam 134 and the shifter carriage C is released from the lug 65.

Extending to the center of the turn-table T is a centering arm 147 secured to the shifting bar 140 and provided with a center locating pin 148. As the record R passes to the turn-table the pin 148 on the centering arm 147 is raised until properly positioned on turn-table T. As best shown in Figs. 1, 11, 12, 13 and 14 a curved bearing 20 bracket 149 firmly secured to the upright post 24, extends downward to form a bearing 150 and to the right to form a bracket 151 on which a swivel collar 152 is pivoted at 153. A turning rod 154 centered in the bearing 150 is connected with the pin 155 to a universal joint 156 through which a tone arm tube 157 is passed. Joint 156 terminates at the top in an eccentric post 158 clearly shown in Fig. 12. The turning rod 154 also extends downward in the bearing 150 and has a 30 collar 159 with an extending rod 160 secured to operate a push switch 161 when desired.

A sound box 162 is secured at the inner end of the tone arm tube 157 and an eccentric collar 157 is disposed above a track bar 163. At the 35 rear of the tube 157 a weight 164 is fastened to help counter-balance the tone arm when swung to the starting position on record R. An electric conductor 165 passes through the tone arm tube 157 from the sound box 162, to the amplifier (not 40 shown). A lug 166 on the centering arm 147 holds a pivot pin 167 on which one end of the track bar 163 is pivoted. The opposite end of track bar 163 is also pivotally connected at 168 to a stationary lug extending upward from the 45 supplemental frame 35. An adjustable stop plate 169 limits the outward swing of the sound box 162 at the point of the eccentric collar 157.

A rod 170 attached to swivel collar 152 and extending substantially parallel to centering arm 50 147 passes through a lug 171 on that arm, the pivot 153 of the swivel collar is so positioned that if the free end rod 170 is raised the swivel collar will be rotated. A second rod 172 also projects from swivel collar 152 and passes directly in front 55 of eccentric post 158 on universal joint 156 which carries the tone arm tube (see Figs. 12 and 14). With this arrangement when centering arm 147 is raised when the playing of a record has been completed to lift the centering pin 148 out of 60 engagement with the center hole of the record, the inner end of the track bar 163 which is pivoted to the centering arm, is raised so that the track assumes an outwardly sloping position down which the tone arm and sound box will tend to 65 slide. Many automatic phonographs depend entirely upon such a sloping track bar to move the reproducer outwardly to the position which it must assume to begin the playing of a record. Because of the weight of inertia of the tone arm 70 recorder and the possibilities that the track may become dirty or sticky the slope of the tone arm track of such machines must be made unnecessarily steep to insure that these parts will, in fact, be given the necessary motion. The result is that 75

the tone arm and reproducer have gained considerable momentum when the stop plate is reached and receive a heavy jar which is detrimental to the delicate parts of the reproducer.

5 By the arrangement described above when the centering arm 141 is tilted upwardly rod 170 is also swung upwardly with the result that swivel collar 152 is turned and rod 71 swung to engage and press against eccentric pin 158. This 10 pressure of rod 172 against pin 158 results in an outward swinging of the tone arm and recorder. Because of this positive mechanical movement the slope of track bar 163 need not be great, with the result that the speed of outward swing of the 15 tone arm and reproducer may be very low so that when it strikes stop plate 169 its momentum will be so low that no shock detrimental to the delicate parts of the reproducer will result.

Referring to Figs. 9 and 10 a lug 173 adjusted 20 at 173' on the supplemental frame 35 has centered at its upper end the pivot pin 174 extending toward the record R. A groove pilot 175 swings on the pivot pin 174 and an arm 176 projecting outwardly has a counter-weight 177 adjustably 25 fixed near its end. A stop pin 178 secured in the lug 173 limits the movement of counter-weight 177. As clearly shown at Fig. 9 the sound box 162 has passed from the central part of the record R to its outer limit due to the incline of the 30 track bar 163 and its coordinating parts. At the same time the sound box 162 contacts with a curved surface 179 on the groove pilot 175 and as the track bar 163 is lowered will correctly position 35 the needle 180 in the starting groove of the record R (see Fig. 10).

The usual mode of operation is to depress knob 190 in the front of the cabinet. This opens a circuit switch 191 and permits the operator to 40 select a favorite composition from the program by turning the knob in a clockwise direction until the point 121 indicates that the record desired is in position to be shifted from the magazine to the turn-table. As long as the knob 190 is depressed the circuit is open. The mechanism 45 will not function until the pressure is released and one or more coins are deposited in the coin slot 192. Conductors 187 and 188 lead from an ordinary source of electric current to a driven contact drum 204 and a change motor 130 respectively. A branch 189 leads to the turn-table motor 32. At the time the coin is deposited the lamp 193 notifies the operator and a magnetic circuit is closed by the coin between the conductors 194 and 195. The magnet 196 consequently attracts the armature 197 which is provided 55 with an escapement mechanism 198 which turns the ratchet wheel 199 in a clockwise direction at the rate of one tooth for every impulse imparted to magnet 196 by the deposit of a coin. 60 A master switch 200 closes the line 201 leading to the phonograph motor 32, at the same time establishing a circuit through the lines 202, the circuit switch 191 (which is normally closed), to the contactor 203 on the drum 204. This contact drum 204 revolves with the shaft 78 and makes one complete turn for every coin deposited. The central contactor 205 is constantly in circuit on the drum 204 but the portions aligned with the 65 contactors 203 and 206 have insulated inserts 207 arranged for starting and stopping the motor at certain intervals. From the contactor 203 the circuit passes to contactor 205 to the line 208 which completes the circuit to the change motor 70 75 130 which revolves the shaft 78 a half turn and

with the mechanism in motion the shifting carriage C takes a record from magazine M and deposits it on turn-table T. At the same time the centering pin 148 is lowered and the needle 180 deposited on the record. When the record starts 5 to play the change motor 130 is thrown out of circuit because the drum 204 has turned so that the insulated insert 207 breaks the circuit of line 209. When a record has been played the sound box 162 has travelled the full distance across it. 10 Then a pin 160 turning with the tone arm tube 157 in the bearing 150 presses against the push switch 161 again closing the circuit through the line 209 starting the change motor 130 at which time the centering pin 148 releases the record and 15 allows the carriage C to return the record to magazine M. The shaft 78 has a cam arm 210 secured to same which as it is nearing the end of a complete cycle, pushes the lever 211 to the right, the lower end having the connecting rod 212 fastened to a pawl mechanism 213. This advances the ratchet wheel 199 one notch to the left at each complete revolution of the shaft 78 or for each coin deposited. A pin 214 secured to the ratchet wheel 199 is advanced toward the 25 switch arm 215 in successive steps until the pin 214 pushes the arm 215 downward disconnecting the master switch 200, at which time the whole mechanism is disconnected from the incoming line. 30

Referring to Figs. 1, 3 and 11 an advancing arm 216 secured at the shaft 78 is in direct alignment with the sprocket 96 on the shaft 92. As the shaft 78 has nearly completed a turn an insert 217 on the arm 216 engages the sprocket 96 to advance same the distance of one tooth and, consequently, raising the magazine M so that the next record R is in alignment with the turn-table. 35

We claim:

1. In an automatic talking machine, the combination of a turn-table, a vertically movable magazine for a multiplicity of records adjacent thereto, means for raising said magazine from its lowest to its highest position and for then releasing it so that it can again move directly to its lowest position, and means on said magazine raising means for maintaining it in releasing position during the downward movement of the magazine. 45

2. In an automatic talking machine, the combination of a turn-table, a vertically movable magazine for a multiplicity of records adjacent thereto, means for raising said magazine from its lowest to its highest position and for then releasing it so that it can again move directly to its lowest position, and means on said magazine raising means for maintaining it in releasing position during the downward movement of the magazine and for then releasing said last mentioned means. 55

3. In an automatic talking machine, the combination of a turn-table, a vertically movable magazine for a multiplicity of records adjacent thereto, means for raising said magazine from its lowest to its highest position and for then releasing it so that it can again move directly to its lowest position, and means for maintaining said last mentioned means in releasing position during the downward movement of the magazine, said magazine raising and releasing means consisting of a spiral cam having a substantially radial 65 slot connecting the lowest and highest points of its camming surface. 70

4. In an automatic talking machine, the combination of a turn-table, a vertically movable magazine for a multiplicity of records adjacent 75

thereto, means for raising said magazine from its lowest to its highest position and for then releasing it so that it can again move directly to its lowest position, and means for maintaining said last mentioned means in releasing position during the downward movement of the magazine, said magazine raising and releasing means consisting of a raising arm engaging with said magazine and having a cam roller thereon, a spiral cam engaging with said roller whereby said arm may be swung upwardly to raise said magazine from its lowest to its highest position when said cam is rotated through one complete revolution, said cam being provided with a radial slot connecting the highest and lowest points of its surface through which said roller can pass directly to the lowest part of said cam surface, one wall of said slot also cooperating with said roller during the downward movement of said magazine 20 to lock said cam against rotation.

5. In an automatic talking machine, the combination of a turn-table, a vertically movable magazine for a multiplicity of records adjacent thereto, means for raising said magazine from its lowest to its highest position and for then releasing it so that it can again move directly to its lowest position, and means for maintaining said last mentioned means in releasing position during the downward movement of the magazine, said magazine raising and releasing means consisting of a raising arm engageable with said cam and having a cam roller thereon, a spiral cam engaging with said roller whereby said arm may be swung upwardly to raise said magazine from its lowest to its highest position when said cam is rotated through one complete revolution, means for imparting to said cam a series of uniform fractional revolutions in one direction only to intermittently and progressively raise said magazine, said cam also being provided with a slot connecting the highest and lowest points of its surface through which said roller can pass to permit said raising arm and said magazine to drop directly from its highest to its lowest position, the sides of said slot also cooperating with said roller while said arm and said magazine are moving downwardly to lock said cam against rotation during the descent of the magazine.

6. In an automatic talking machine, the combination of a turn-table, a vertically movable magazine for a multiplicity of records adjacent thereto, means for raising said magazine from its lowest to its highest position and for then releasing it so that it can again move directly to its lowest position, and means for maintaining said last mentioned means in releasing position during the downward movement of the magazine, said magazine raising and releasing means consisting of a raising arm engaging with said magazine and having a cam roller thereon, a spiral cam engageable with said roller whereby said arm may be swung upwardly to raise said magazine from its lowest to its highest position when said cam is rotated through one complete revolution, said cam being provided with a radial slot engaging the highest and lowest points of its surface through which said roller can pass directly to the lowest part of said cam surface, one wall of said slot also cooperating with said roller during the downward movement of said magazine to lock said cam against rotation, the inner end of said wall terminating a sufficient distance from the surface of said cam to permit said roller to pass under it to release said cam for further rotation.

7. In an automatic talking machine the combination of a supporting frame, a record magazine, a turn-table adjacent the cam, means for shifting the magazine to bring a record therein into registry with the turn-table, a rotatable timing shaft, means operated by the timing shaft when rotated to automatically transfer the registered record from the magazine to the turn-table and to return the record to the magazine after the playing of the record is completed, means for positively locking the magazine against movement in any direction while the record is on the turn-table, said locking means comprising a toothed detent plate on said magazine, a lever having teeth engageable with the teeth on said detent plate, and means for engaging said teeth when a record is shifted from the magazine to the turn-table and for disengaging said teeth when the record is transferred back again into the magazine and while the magazine is being shifted to bring another record into registry with the turn-table.

8. In an automatic talking machine the combination of a supporting frame, a record magazine, a turn-table adjacent the cam, means for shifting the magazine to bring a record therein into registry with the turn-table, a rotatable timing shaft, means operated by the timing shaft when rotated to automatically transfer the registered record from the magazine to the turn-table and to return the record to the magazine after the playing of the record is completed, means for positively locking the magazine against movement in any direction while the record is on the turn-table, said locking means comprising a toothed detent plate on said magazine, a lever having teeth engageable with the teeth on said detent plate, and means for engaging said teeth when a record is shifted from the magazine to the turn-table and for disengaging said teeth when the record is transferred back again into the magazine and while the magazine is being shifted to bring another record into registry with the turn-table, said last mentioned means being operated from the timing shaft.

9. In an automatic talking machine, the combination of a turn-table, a vertically movable magazine for a multiplicity of records adjacent thereto, manual and automatic means for raising said magazine from its lowest to its highest position and for then releasing it so that it can again move directly to its lowest position, and means on said raising means for maintaining said last mentioned means in releasing position during the downward movement of the magazine.

10. In an automatic talking machine, the combination of a turn-table, a vertically movable magazine for a multiplicity of records adjacent thereto, manual and automatic means for raising said magazine from its lowest to its highest position and for then releasing it so that it can again move directly to its lowest position, means for maintaining said last mentioned means in releasing position during the downward movement of the magazine, and means for automatically rendering said manual means inoperative when said talking machine is in operation.

11. In an automatic talking machine the combination of a turn-table, a motor for rotating said turn-table, a vertically movable magazine for a plurality of records, means for progressively raising said magazine from its lowest to its highest position to bring each of said records successively into registration with said turn-table and for then releasing it so that it can move directly to

- its lowest position, means for shifting each record when so registered from said magazine to said turn-table and for returning it to said magazine, a second electric motor for driving said 5 raising and shifting means, electric circuits for said motors, a master switch common to both circuits, manual means for raising said magazine in the same manner but independently of said motor operating means, and for opening said 10 master switch while said manual means is being operated, and means for rendering said manual means inoperative upon said magazine when said second motor is operating.
12. In an automatic talking machine the combination of a turn-table, a motor for rotating said turn-table, a vertically movable magazine for a plurality of records, means for progressively raising said magazine from its lowest to its highest position to bring each of said records successively into registration with said turn-table and for then releasing it so that it can move directly to its lowest position, means for shifting each record when so registered from said magazine to said turn-table and for returning it to said 15 magazine, a second electric motor for driving said raising and shifting means, electric circuits for said motors, a master switch common to both circuits, manual means for raising said magazines in the same manner but independently of said motor operating means, said manual means being operatively associated with said master switch to maintain it open while said manual means is being operated.
13. In an automatic talking machine, the combination of a turn-table, a centering pin for centering a record upon said turn-table, said pin being mounted upon a vertically rockable arm whereby it may be engaged and disengaged from said record, a tone arm provided with a

reproducer adapted to follow the sound track of the record, a track rockable with said centering pin arm to lift said reproducer from the record when the playing of the record is completed and to then cause said reproducer to swing to a position approximately overlying the beginning of the record groove and then to lower it again upon the record, an auxiliary means cooperating with said track in swinging said reproducer which consists of a pin on said tone arm eccentric of the bearing upon which it swings, and means engageable with said pin operated by the upward rocking of said centering pin arm to swing said pin and said reproducer.

14. In an automatic talking machine, the combination of a turn-table, a centering pin for centering a record upon said turn-table, said pin being mounted upon a vertically rockable arm whereby it may be engaged and disengaged from said record, a tone arm provided with a 20 reproducer adapted to follow the sound track of the record, a track rockable with said centering pin arm to lift said reproducer from the record when the playing of the record is completed and to then cause said reproducer to swing to a position approximately overlying the beginning of the record groove and then to lower it again upon the record, an auxiliary means cooperating with said track in swinging said reproducer which consists of a pin on said tone arm eccentric of the bearing upon which it swings, means engageable with said pin operated by the upward rocking of said centering pin arm to swing said pin and said reproducer, and means associated with said track for retarding the lowering of the 25 reproducer and for guiding it into the record groove.
